UNITED STATES PATENT OFFICE.

ORLANDO KLING, OF DENVER, COLORADO.

KNOCKDOWN CRATE.

1,107,312.

Specification of Letters Patent. Patented Aug. 18, 1914.

Application filed November 13, 1912. Serial No. 731,074.

To all whom it may concern:

Be it known that I, ORLANDO KLING, a citizen of the United States, residing at Denver, in the county of Denver and State 5 of Colorado, have invented certain new and useful Improvements in Knockdown Crates, of which the following is a specification.

10 of which the following is a specimen:
This invention relates to knock down shipping crates, and has for one of its objects to improve the construction and increase the efficiency and utility of devices of this character.

Another object of the invention is to provide a simply constructed device wherein the parts may be separated for shipment in "knocked down" condition and set up where required and without detaching any of the parts.

Another object of the invention is to provide a simply constructed device having protecting means at the corners which operate in a two-fold capacity, as means for coupling the parts and likewise as means for protecting the corners.

25 With these and other objects in view the invention consists in certain novel features of construction as hereinafter shown and described and then specifically pointed out in the claims, and in the drawings illustrative of the preferred embodiment of the invention Figure 1 is a plan view of the improved device. Fig. 2 is a side elevation partly in section. Fig. 3 is a perspective view from the inner side of one of the 30 fastening devices. Fig. 4 is a perspective view of one of the tongue members of the fastening device. Fig. 5 is a view of the base portion of the fastening device viewed from the outside. Fig. 6 is a detached per-

from the outside. Fig. 6 is a detached perspective view from the outside of one of the corner guard members. Fig. 7 is a view from the inside of one of the corner guard members. Fig. 8 is a detached perspective view of the top member. Fig. 9 is a detached perspective view of one of the end members. Fig. 10 is a detached perspective view of one of the side members. Fig. 11 is a detached perspective view of the bottom member. Fig. 12 is a perspective view of one of the seal receiving fastening devices. Fig. 13 is a detached perspective view of one of the locking pins.

55 Corresponding and like parts are referred to in the following description and indicated in all the views of the drawings by the same reference characters.

The improved device may be formed of any required size and of any required proportion, and it is not desired to limit the invention in this respect.

The improved device comprises a bottom member 10, end members 11—12, side members 13—14 and a top member 15, preferably of wood of any required thickness, the thickness of the material depending upon the 65 purposes for which the crate or casing is to be used. The bottom member is surrounded by a frame formed of L bars with one web of each bar bearing over the lower side of the bottom and the other web of each bar 70 projecting above the upper face of the bottom, as shown in Fig. 11. The L bars at the ends of the bottom are designated by the character 16 and are provided with longitudinal clefts at their ends and the portions of 75 the bars in advance of the clefts bent at right angles to the longitudinal webs and overlapped, as shown in Fig. 11. The L bars at the sides of the bottom are designated by the character 17 and extend at the ends over the 80 overlapped portions of the end bars. The members 16—17 are secured in any suitable manner, preferably by riveting. The bottom 10 is secured to the sides by the same screws or other fastening devices by which 85 the guard members 20 are secured, as represented in Figs. 1 and 2. The top of the improved device is likewise provided with terminal L bars 18 and side L bars 19 and are practically duplicates of the L bars of the 90 bottom member and provided with longitudinal clefts with the portions externally of the clefts bent at right angles and overlapped, as shown, and fastened in any suitable manner to the top. Bearing beneath 95 the bottom member at the corners are guard devices represented respectively as a whole at 20, preferably formed, as shown in Figs. 6 and 7, by being struck up from a sheet of metal, preferably steel, with one edge rel- 100

metal, preferably steel, which is relatively thin and the remaining edges relatively thick. The thinner portion of the corner guard members is designed to receive the holding rivets or other fastening devices 21, while the outwardly swelling or thickened portion is designed to support the device and receive the impact when the device is moved from place to place, or up ended, or otherwise moved about. The top 15 and ends 11 and 12 are likewise provided with other sets of the guard members 20 and arranged in substantially the same man- 105 110

ner. The guard members 20, it will be noted, bear over the overlapped corners of the L bars and are riveted or otherwise securely fastened to the top and bottom members.

5 By providing the top member 15 with the guard members the case is protected and guarded from injury when over turned, as will be obvious. Each of the guard members is provided with a recess 22 at its inner 10 end and opening outwardly so that holding devices such as rivets, or screws may be inserted into the structure, as hereafter explained.

The end members 11—12 are constructed 15 precisely alike and are provided with attachments which are likewise precisely alike, so that the description of one will suffice for both. Each of the end members is provided at each of its corners with a recess 20 23, and bearing against the inner face of each end member adjacent to its corners is a plate 24 having an integral lug 25 engaging in the adjacent recess 23. Each plate 24 is likewise provided with inwardly directed 25 lugs 26 spaced apart and likewise spaced from the end edges of the end members.

Bearing over the end of each end member is an L bar, represented as a whole at 29, with one web of the L bar bearing over 30 the outer face of the end member and the other web extending beyond the inner face of the end member. By this means spaces are left between the lugs 26 and the adjacent web of the L member 29 and into this space 35 the ends of the sides 13—14 are received. By this means the sides are effectually held from outward movement by the adjacent webs of the L bars 29 and against inward movement by the lugs 26. The L bars 29 40 are further secured by screws or like detachable fastening devices 27 which are passed through the outer faces of the L bars and through the lugs 25 and likewise through the overlapped terminals of the end L bars 18 45 of the top with the end edges between the adjacent webs of the L bars 29. Attached to the inner faces of the sides 13—14 near each corner is a small plate 28 enlarged at the outer end, as shown at 30, and adapted 50 to fit between the lugs 26 and the adjacent web of the L bars 29. When thus assembled a pin 31 is inserted through the lugs 26 and the enlargement 30 of the member 28 and thus coupling the side members to the end 55 members. The upper end of the pin 31 is enlarged laterally into a head and received in a counter-bore in the aperture in the upper lug 26 so that the pin is prevented from passing entirely through the lugs and 60 at the same time prevented from longitudinal movement when the top and bottom members are disposed in position.

The top member with its attachments is constructed as shown in Fig. 8, the end members constructed as shown in Fig. 9, and the

side members constructed, as shown in Fig. 10, while the bottom member is constructed as shown in Fig. 11, and the parts thus arranged with the attachments applied will be crated or otherwise supported for shipment 70 "knocked down."

After the body members are assembled as illustrated in Figs. 1 and 2, one of the guards 20 is located beneath the L bars of the bottom member at their overlapping 75 corners, and one of the guard members likewise located above the top member at each corner and engaging over the overlapping portions of the L bars with the securing devices 21 engaging through the L bars and 80 respectively into the body members 10—15. By this means the members 20 perform the twofold function of guards to protect the body members and the L bars, and likewise to reinforce the L bars at their junctures, or 85 where they are overlapped. After the parts are assembled the members 20 are attached at the corners of the end body members and engaging over the L bars at their junctures in the same manner as illustrated in Figs. 90 1 and 2. One of the fastening devices 21 of each of the members 20 which are engaged over the end members passes through the L bars and into the projecting lugs 25 of the base members 24, as shown, so that the parts 95 are thoroughly and firmly fastened together and all danger of dismemberment obviated.

The upper guard members of the casing are attached to the ends of the casing near its upper edges and each provided with a 100 seal wire receiving aperture 32, while the head of the fastening device 27 is likewise provided with a seal wire receiving aperture 33, so that a suitable seal may be applied to secure the cover in place after the fastening 105 devices 27 are turned "home."

Having thus described the invention what I claim is:

1. In a knock-down crate, a body including bottom side and end members and a top 110 member, L bars bearing upon the confronting edges of said body members and overlapping at their terminals, fastening devices each including a base attached to one of the end members and with a lug extending 115 through the same, fastening devices attached to the side members, a set of guard members bearing upon said top and bottom members and engaging over the L bars at their overlapping terminals, a second set 120 of guard members engaging said end members, means for connecting the fastening members of said ends to the fastening members of said sides, and means for fastening the first-mentioned guard members to said 125 L bars and the lugs and operating to reinforce and protect the L bars and the body members.

2. In a knock down crate, a body including bottom side and end members and a top 130

- member bearing upon the body members, L bars bearing upon the confronting edges of said body members and overlapping at their terminals, guard members bearing 5 upon said top and bottom members and engaging over the L bars at their overlapping corners, means for fastening said guard members to said body members and to said L bars and operating to reinforce and protect the same, fastening devices each including a base and a tongue attached respectively to the end and side members, each base having a lug extending through the body member to which it is attached and engaged by the adjacent L bar, fastening means connecting each of said tongues to one of the bases, and fastening means operating respectively through the L bars and into the base lugs. 10 15 20 25
3. In a knock down crate, a body including bottom side and end members and a top member bearing upon the body members, L bars bearing upon the confronting edges of said body members and overlapping at their terminals, fastening devices each including a base and a tongue attached respectively to the end and side members, each base having a lug extending through the body mem-
- ber to which it is attached and engaged by the adjacent L bar, a pin connecting each of 30 said tongues to one of the bases, and fastening means operating respectively through the L bars and into the base lugs. 35
4. In a knock down crate, a body including side and end members and a top member, bars bearing over the confronting edges of said body members, guard members bearing upon said side and end members and engaging over the bars, fastening devices including bases having coacting tongues and 40 attached respectively to the end and side members, the bases which are attached to the end members being provided respectively with lugs which extend through the adjacent end member and are engaged by 45 the adjacent bar, fastening means connecting said tongues, and fastening means operating respectively through the guards and bars of the end members and into the lugs. 45

In testimony whereof I affix my signature 45
in presence of two witnesses.
